COMBINATION LOCK

Filed Jan. 20, 1928

UNITED STATES PATENT OFFICE

MAURICE SAMBURG, OF BROOKLYN, NEW YORK, ASSIGNOR TO LOCK PATENTS HOLDING CORPORATION, OF NEW YORK, N. Y., A CORPORATION OF NEW YORK

COMBINATION LOCK

Application filed January 20, 1928. Serial No. 248,223.

My invention relates to improvements in permutation of combination locks; and the same has for its object more particularly to provide a simple, compact and reliable device which may be conveniently operated to lock or unlock the same; and which cannot be readily unlocked by unauthorized persons surreptitiously.

Further, said invention has for its object 10 to provide a device of the character specified which comprises a very few inexpensive parts assembled for efficient and reliable operation.

Further, said invention has for its object to provide a device of the character specified 15 in which the permutation mechanism thereof cannot be manipulated to release the lock-controlling member by use of the sense of touch or hearing.

Further, said invention has for its object 20 to provide a device of the character described in which the adjustable parts thereof are disposed one upon the other in exposed position to provide a compact structure permitting of the convenient manipulation 25 thereof.

Further, said invention has for its object to provide a device of the character specified 30 in which the locking means thereof may, if desirable, be locked or unlocked without prior operation of the permutation mechanism to release the member controlling said locking means.

Further, said invention has for its object to provide a device of the character specified 35 in which said permutation mechanism, when moved out of registering position, may be rendered either operative or inoperative to lock the controlling or actuating member for the locking means depending on the position of said controlling member relative to said mechanism.

Further, said invention has for its object to provide a device of the character specified in 40 which the tumblers thereof are disposed one upon the other in exposed position to permit of the manipulation of each thereof independently, and in which the finger piece of the controlling member for the locking means extends over said tumblers in close relation 45 thereto and conforms in contour therewith.

Other objects will in part be obvious, and in part be pointed out hereinafter.

To the attainment of the aforesaid objects and ends my invention consists in the novel features of construction, and in the combination, connection and arrangement of parts hereinafter more fully described and then pointed out in the claims.

In the accompanying drawing:

Fig. 1 is a plan of one form of locking device constructed according to and embodying my invention;

Fig. 2 is a side view thereof, parts being broken away;

Fig. 3 is a bottom plan thereof;

Fig. 4 is an enlarged sectional view thereof on the line 4—4 of Fig. 1;

Fig. 5 is a cross section showing the parts in position permitting of rotation of the spindle or actuating member;

Figs. 6, 7 and 8 are views similar to Fig. 5, showing the parts in other positions;

Fig. 9 is an exploded view of the spindle and cam; and

Fig. 10 is an exploded view of the tumblers and supporting plate therefor.

Referring to the drawings, the device preferably comprises a plate or support 10 having a downwardly or rearwardly extending flange 12 providing a space 14 at one side of said plate for the reception of the locking means hereinafter more fully described. An annular boss or bearing 16 extends from the opposite side of said plate 10 and has a radial slot 18 therein loosely receiving the single locking member or dog 20. The dog 20 is slightly longer than the slot 18, and is provided with rounded longitudinal edges or cam surfaces, as indicated at 22.

An actuating member or spindle 24 is rotatably disposed within the annular bearing 16 and extends at the inner end thereof into the space 14 below the plate 10. The spindle 24 is provided with a pair of longitudinal recesses or grooves 26 and 28 of unequal size disposed at opposite sides thereof. The smaller groove 26 is adapted to receive the dog 20 which closely fits the same for locking the spindle against rotation as hereinafter more fully described, and the larger grooves 28 in

another position of the spindle 24 is also adapted to receive the dog 20, but to permit of the partial rotation of the spindle 24 relative thereto to control the locking means.

The radial position of the dog 20 relative to the spindle 24 is controlled by suitable permutation mechanism, such as the tumblers or members 30, 32 and 34 provided with openings 36, 38 and 40 of uniform size, the uniformity in the size of the openings being insured preferably by forming the several openings by the same machine during the manufacture thereof. The inner edges of the several members 30, 32 and 34 have cam notches 42, 44 and 46 therein for receiving the dog 20. The members 30, 32 and 34 are disposed about said boss 16 which closely fits the openings 36, 38 and 40. The members 30, 32 and 34 are disposed one above the other in exposed position to permit of the actuation of each thereof independently, and the same are preferably of successively decreasing diameter providing a step formation having the tread portions thereof provided with the usual calibrations or indicia for working the combination as indicated at 48. The tumbler 34, however, is preferably formed as a cover washer, the same having a flange 50 encircling the end of the boss 16 and a transverse portion 52 extending over the end thereof. The opening 40 of the member 34 is formed in said flange 50, and the notch 46 thereof is also formed in the flange 50. The member 34 has a central opening 54 receiving the spindle 24.

The several members 30, 32 and 34 closely fit the boss 16 to prevent play relative thereto so that the tumblers cannot be manipulated by unauthorized persons to unlock the device by the sense of touch or hearing without knowing the combination. Relative play between the members or tumblers is largely prevented by making the openings thereof of uniform size as above described.

A finger piece or actuating portion 56 is attached to or formed on the outer end of the spindle 24. This member 56 preferably comprises a pair of arms 58 extending radially outwardly in close relation to the several tumblers 30, 32 and 34 and conforming in contour with the contour thereof to provide a compact structure, and to provide a finger piece which does not unduly cover the calibrations 48 so as to interfere with the reading thereof. In the embodiment of the invention illustrated the inner faces 60 of the arms 58 are of step formation, corresponding to the formation of the tumblers and the same are disposed in close relation thereto, the ends 62 of the arms 58 being substantially flush with edges of the lower tumbler 30.

A pair of stops 64, 66 are disposed at diametrically opposite sides of the permutation mechanism upon the plate 10. A cooperating member or pin 68 carried by one end of

the piece 56 is adapted to engage the stops 64 and 66 to limit the movement of the member 56 and spindle 24 as the same are rotated through an arc of 180°. The stop 64 is so located that, when the pin 68 engages the same as shown on the drawing, the groove 26 becomes aligned with the dog 20. When the pin 68 engages the stop 66 the groove 28 becomes aligned with the dog 20.

The spindle 24 is adapted to control any suitable locking means disposed within the space 14. I have illustrated as one example, a locking detent or member 70 pivoted at 72 intermediate its ends, and having an end adapted to engage the cooperating locking member 74, illustrated as a notched stud of the usual luggage hasp 76 adapted to pass through an opening 77 in the plate 10. A spring 78 normally maintains the member 70 pressed towards the stud 74. A cam 80 secured to the inner end of the spindle 24 at right angles to the grooves 26 and 28 cooperates with the opposite end of the lever or detent 70 to effect the disengagement thereof from the stud 74.

In operation, assuming it is desired to unlock the device, the several tumblers 30, 32, 34 are moved in accordance with a given combination so that the several notches 42, 44 and 46 become aligned with each other and register with the dog 20, as shown at Fig. 5. When the spindle 24 is partially rotated away from stop 64, the parts then assume the position shown at Fig. 7, the member 20 being forced into the notches by the cam action of the rotatable spindle. This movement retracts the lever 70. When it is desired to release the member 70 and lock the spindle, the spindle is rotated in the opposite direction until the pin 68 engages the stop 64. One or more of the tumblers are then rotated to bring their notches out of alignment with slot 18, as shown at Fig. 6, for example, which forces the dog 20 by cam action of the notches into the groove 26, the dog being retained therein against retraction and securely locking the spindle against movement.

In some instances it is desirable to be able to retract the lever 70 to unlock the device without working the combination. For this purpose, the spindle 24, when the same is rotated to unlock the device, is rotated clockwise, looking at Fig. 7, until the pin 68 thereof engages the stop 66. The relatively wide groove 28 will then register with the dog 20, the latter being received therein, as shown at Fig. 8, when the tumblers are rotated out of registering position. It is to be noted that the size or width of the groove 28 is such as to permit of rotation of the spindle relative to the dog 20 to actuate the detent 70 without first requiring manipulation of the tumblers to place the same in registering position with the dog 20. This permits of the

actuation of the member 70 even though the notches of the tumblers 30, 32 and 34 do not register with the dog 20.

The lock embodying my said invention is 5 adapted for general use, as well as for use on luggage, such as trunks, valises, brief cases, and the like, and on safety deposit boxes, lockers, etc., where compactness and reliability of operation are desired. The lock of 10 the present invention may be used to operate any kind of locking mechanism, such as on doors to operate a sliding bolt, etc., inasmuch as the operating or controlling spindle is locked against movement when the locking mechanism is locked.

By my invention it is permitted to lock and unlock the device, either by first manipulating the tumblers in accordance with the combination therefor to release the actuating 20 member for the locking means, or without manipulation of said tumblers, as desired.

The few parts of the device, including the tumblers and finger piece thereof, are in exposed position to permit of the convenient 25 manipulation thereof, and the same are compactly arranged one upon the other to reduce the height thereof above the surface of the plate 10. The parts of the improved lock being entirely exposed and compactly 30 assembled adapts the lock for ready attachment to any object with very little trouble and without the necessity of extensive alterations or changes.

I claim:

35 1. A lock comprising an actuating member, locking means controlled thereby, permutation mechanism adapted to be moved from and to registering position to lock and release said actuating member, and means movable into operative relation to said permutation mechanism to permit of movement thereof relative to said actuating member and to render the former inoperative to lock the latter when said permutation mechanism is 40 moved from registering position, whereby to permit of the control of the lock independently of the position of said permutation mechanism.

50 2. A lock comprising a rotatable actuating member, locking means controlled thereby, permutation mechanism adapted to be moved from and to registering position to lock and release said actuating member, and means controlled by the position of said actuating member to render said permutation mechanism inoperative to lock said actuating member when said permutation mechanism is moved from registering position.

55 3. A lock comprising a rotatable actuating member, locking means controlled thereby, permutation mechanism for locking and releasing said actuating member, said actuating member having means adapted to oppose said permutation mechanism in certain of the 60 positions of said actuating member to render

said permutation mechanism in the normal locking positions thereof inoperative to lock said actuating member.

4. A lock comprising a rotatable actuating member, locking means controlled thereby, 70 permutation members cooperating with said actuating member in one position thereof to effect the locking thereof, said actuating member having means cooperating with said permutation members in another position of said actuating member to render the former inoperative to lock said actuating member.

75 5. A lock comprising a rotatable actuating member having a plurality of recesses therein, locking means controlled thereby, 80 and permutation mechanism cooperating with said actuating member; one of said recesses in one position of said actuating member cooperating with said permutation mechanism to effect the locking of said actuating member, and the other of said recesses in another position of said actuating member cooperating with said permutation mechanism to render the same inoperative to lock said actuating member.

85 6. A lock comprising a support, an annular bearing extending from said support and having a radial slot therethrough, an actuating member rotatably disposed within said bearing and having recesses of unequal size 90 in spaced relation thereon, locking means controlled thereby, a plurality of notched tumbler members disposed about said annular bearing, and a dog disposed in said slot; the smaller of said recesses receiving said dog in the locking position of said tumbler members to effect the locking of said actuating member, and the larger of said recesses receiving said dog to permit of movement of said actuating member irrespective of the position of said tumbler members.

95 7. A lock comprising a plate, an annular bearing extending from one side of said plate and provided with a radial slot, a dog disposed within said slot, a plurality of tumblers 100 rotatably disposed about said bearing, and each thereof having an interior notch, a spindle rotatably disposed within said bearing and provided with a plurality of longitudinal grooves of unequal size adapted to receive said dog, and locking means at the opposite side of said plate actuated from said spindle.

105 8. A lock comprising a support, an actuating member thereon, locking means controlled thereby, permutation mechanism adapted to be moved from and to registering position to lock and release said actuating member, a plurality of means on said actuating member adapted to be moved into one position relative to said permutation mechanism to permit of the locking of said actuating member and into another position to render said permutation mechanism inoperative to lock said actuating member, and stop means on said actuating 110 member.

member and said support for indicating said positions of the actuating member.

9. A lock comprising a plate, a bearing boss on said plate provided with a slot, a plurality of disks rotatably disposed about said boss, one above the other in exposed position to permit of the manual actuation of each thereof independently, and each of said disks having an interior notch, a spindle rotatably disposed within said boss and provided with a plurality of longitudinal grooves, a single dog within said slot adapted to be received in said notches when the same are aligned therewith and to be received in each of said grooves as desired, and locking means actuated by said spindle.

10. A lock comprising a support, an annular boss extending therefrom, a spindle rotatably disposed within said boss, a plurality of disk tumblers of successively decreasing diameter rotatably disposed about said boss, one above the other in exposed position to permit of the manual actuation of each thereof independently, means interposed between said spindle and said tumblers for effecting the locking of said spindle by said tumblers, locking means at the opposite side of said support controlled by said spindle, and a finger piece extending from the outer end of said spindle over said several tumblers in close relation thereto, and conforming in contour with the contour thereof.

11. A lock comprising a support, an annular boss extending from one side thereof and having a longitudinal slot therethrough, a spindle rotatably disposed within said boss and having a longitudinal groove therein adapted to register with said slot, a plurality of disk tumblers of successively decreasing diameter disposed about said boss, one above the other in exposed position to permit of the manual actuation of each thereof independently, and having notches at the inner edges thereof adapted to register with said slot, a dog disposed within said slot and received within said groove to lock said spindle and received within said notches to unlock said spindle, locking means at the opposite side of said plate controlled by said spindle, and an actuating portion at the outer end of said spindle including arms conforming in contour with the contour of said tumblers of successively decreasing diameter and disposed in close relation thereto.

12. A lock comprising a support, an annular boss extending from one side thereof and having a longitudinal slot therethrough, a spindle rotatably disposed within said boss and having a longitudinal groove therein adapted to register with said slot, a plurality of disk tumblers of successively decreasing diameter disposed about said boss, one above the other in exposed position to permit of the manual actuation of each thereof independently, and having notches at the in-

ner edges thereof adapted to register with said slot, a dog disposed within said slot and received within said groove to lock said spindle and received within said notches to unlock said spindle, means on said spindle for receiving said dog to render the same inoperative to lock said spindle, locking means at the opposite side of said plate controlled by said spindle, a finger piece at the outer end of said spindle including arms conforming radially in contour with the contour of said tumblers of successively decreasing diameter, and disposed in close relation thereto, and stop means on said support and said finger piece for limiting the movement of said spindle.

13. A lock comprising a plate having an aperture to receive a locking stud, a detent pivoted intermediate its ends to said plate, one end of said detent being movable to intersect said opening, a spindle having a cam movable in either direction into engagement with said detent to move it out of intersection with said opening, permutation means for locking said spindle in a given position against movement in one direction, and means for permitting limited movement of said spindle in any position of the permutation means.

14. A lock comprising a plate having an aperture therein, a spindle, permutation means concentric with said spindle, cam means secured to said spindle, and a detent pivoted to said plate, said detent being movable by said cam out of intersection with said aperture.

15. A lock comprising a plate having an aperture therein, a spindle, permutation means concentric with said spindle, cam means secured to said spindle, a detent pivoted to said plate, said detent being movable by said cam out of intersection with said aperture, and spring means for moving said detent in the opposite direction.

16. A lock comprising a plurality of concentric permutation disks of unequal radius, means for rotatably supporting same, a control spindle concentric with said supporting means, and an arm secured to said spindle and extending therefrom at a right angle, said arm having an interior stepped surface fitted to said disks.

17. A lock comprising a plurality of concentric permutation disks of unequal radius, means for rotatably supporting same, a control spindle concentric with said supporting means, an arm secured to said spindle and extending therefrom at a right angle, said arm having an interior stepped surface fitted to said disks, and stops to limit the movement of said arm in either direction.

18. A lock comprising a plate having a cylindrical boss with a center bore, a slot extending through the wall of said boss from its free end to a point adjacent its base, a

plurality of permutation disks revolvably supported by said boss, each of said disks having an interior notch, a single dog in said slot movable into and out of engagement with said notches, and a control spindle within said boss and having a recess to receive said dog.

19. In a lock, a plate having a circular portion and an extension therefrom, a hollow boss integral with said plate and concentric with said circular portion, a bore concentric with said boss, an aperture through said extension, a flange integral with the edge of said plate and extending therefrom in a direction away from said boss, and locking means pivotally secured to said plate within the chamber formed by said flange and movable into and out of intersection with said aperture.

20. A lock comprising a plate, an annular boss projecting therefrom and having a slot extending through the wall of the boss substantially from end to end thereof, a plurality of permutation disks rotatably disposed about said boss and arranged along said boss substantially coextensively with the length thereof, each of said disks having an interior notch, a dog of a length substantially equal to that of said slot disposed therein and movable into and out of engagement with said notches, a control spindle received within said boss and having a recess for receiving said dog, and a finger piece on said spindle to retain the disks in position on said boss.

21. A lock comprising a plate, an annular boss projecting therefrom and having a slot extending through the wall of the boss substantially from end to end thereof, a plurality of permutation disks of unequal radius rotatably disposed about said boss and arranged therealong substantially coextensively with the length thereof, each of said disks having an interior notch, a dog of a length substantially equal to that of said slot disposed therein and movable into and out of engagement with said notches, a control spindle received within said boss and having a recess for receiving said dog, and a finger piece on the outer end of said spindle extending over said several disks in close relation thereto.

22. A lock comprising a plate, an annular boss projecting therefrom and having a slot extending through the wall of the boss substantially from end to end thereof, a plurality of permutation disks of decreasing diameters rotatably disposed about said boss and arranged therealong substantially coextensively with the length thereof, each of said disks having an interior notch, a dog of a length substantially equal to that of said slot disposed therein and movable into and out of engagement with said notches, a control spindle received within said boss and

having a recess for receiving said dog, a finger piece on the outer end of said spindle extending over said disks and lying in close relation thereto, and stops on said plate lying in the path of said finger piece.

23. A lock comprising a plate, an annular boss projecting from said plate, a plurality of permutation disks rotatably disposed about said boss above said plate, a control spindle rotatably received within said boss means interposed between said spindle and said disks for effecting the locking of said spindle by said disks, a finger piece on the outer end of said spindle overlying said disks, and a member on said spindle at the opposite end thereof below said plate, said member and said finger piece serving to secure the parts together and retain said disks in position about said boss against removal therefrom.

24. A lock comprising a rotatable actuating member, locking means controlled thereby, permutation mechanism, said actuating member having means adapted to align with said permutation mechanism for effecting the locking and release of said actuating member, said actuating member having also means adapted to align with said permutation mechanism to render said mechanism inoperative to lock said actuating member, and stops lying in the path of travel of said actuating member and limiting the movement thereof at positions for aligning said two last named means with said permutation mechanism.

In testimony whereof, I have signed my name hereto.

MAURICE SAMBURG.
